CUT-OUT STANDING TOY

Adele Burns, New York, N. Y.

Application February 13, 1935, Serial No. 6,302

3 Claims. (Cl. 46—40)

This invention relates to new and useful improvements in cut-out standing toys.

The invention has for an object the construction of such a toy, which is characterized by a novel provision, integral with the material composing the cut-out toy, by which the toy may stand.

More particularly, the invention proposes the construction of blanks from which toys may be cut out, said blanks consisting of sheets of material printed or inscribed with congruent front or back parts of figures or objects, contacting at an area or areas which will permit said front and back parts to be superimposed when the parts are cut out and bent at said contacting areas, and said parts to have integral bases adapted to be bent outwards when the parts are superimposed so as to be capable of supporting the toy in an upright position.

Still further the invention proposes an arrangement wherein the sheet or sheets of material are gummed upon the back side so that the front and backs of the cut-out parts may be easily pasted together.

Another one of the objects of this invention is the construction of cut-out standing toys which are characterized by cut-out sheets of material of congruent front and back parts pasted together, said parts to have integral base pieces bent away from each other, and flat base pieces pasted across said base pieces for forming sturdy feet to support the toys in upright positions.

Another one of the objects of this invention is the provision of removable elements covering portions of the gummed material, particularly behind the bases, so that the gummed material may be moistened to paste the front and back parts together without moistening the gummed material of the bases. Thereafter, the removable elements may be removed and the base attached upon the flat support pieces.

Still further the invention proposes the construction of an article as mentioned which is simple and durable and which can be manufactured and sold at a reasonable cost.

For further comprehension of the invention, and of the objects and advantages thereof, reference will be had to the following description and accompanying drawings, and to the appended claims in which the various novel features are more particularly set forth.

In the accompanying drawings forming a material part of this disclosure:

Fig. 1 is an elevational view of a sheet of material with figures inscribed or printed thereon

adapted to be cut out into standing toys, according to this invention.

Fig. 2 is a perspective view of the figures shown in Fig. 1 cutout, and in the process of being formed into a standing toy.

Fig. 3 is a vertical transverse sectional view of the completed toy.

Fig. 4 is a perspective view of cutout pieces of different design.

Fig. 5 is a similar view to Fig. 4, but showing a different design.

Fig. 6 is a perspective view of other cutout pieces of a still further different design, a portion thereof being illustrated uncut.

Fig. 7 is a fragmentary sectional view taken on the line 7—7 of Fig. 6.

In Fig. 1 a sheet of material 10 has been illustrated inscribed or printed with congruent front and back parts 11 and 12, respectively, of the figure of a "chick". These parts are arranged to have a contacting area 13 which will permit the front and back parts to be superimposed when the parts are cut from the sheet 10 and bent along the contacting area. A feature of the invention resides in the fact that the parts 10 and 11 are provided with integral base pieces 14 arranged in such a manner that the cut-out toy may stand. The base pieces 14 are formed with scored lines 15 dividing off flange sections 16 which may be bent outwards away from each other when the pieces are cut out. The back-side of the sheet 10 may be gummed; or paste or other adhesive may be supplied with the sheet for the pasting of the parts together. Preferably, the sheet 10 should be of a cardboard not too heavy for a child to cut. The object of having the parts 10 and 11 connected is that a child may more easily assemble them.

The cut-out pieces should be glued or pasted together to the line where the flanges 16 spread, that is, the line 15. This is clearly illustrated in Figs. 2 and 3. A base piece 17 is then glued or pasted upon the bottom of the flanges and trimmed down to the exact shape of the flanges. The toy is now capable of standing, and movable for the enjoyment of a child.

Larger and more substantial toys may be printed on heavy cardboard, die cut at the factory, and mounted on cardboard bases—to be sold as a completed toy, either singly or in sets. They may also be printed on thin tin or other sheet material, one or more on a sheet and sold in sheets or in bound book forms.

In Fig. 4 the parts 11' and 12' of a turkey are illustrated connected together at the two areas

13'; which areas are arranged so that the front and back parts may be bent along these areas to superimpose them upon each other. While the design of the parts are different, the invention in both cases is the same, in that the parts are equipped with bases 14 having scored lines 15 dividing off the support flanges 16. In other respects, the toy is similar to the one previously described, and its use, operation, and play will readily be understood.

In Fig. 5 the parts 11^b and 12^b of a sail boat are connected together at 13^b. In other respects this form of the invention is identical with the forms illustrated in the previous figures.

In Figs. 6 and 7 another embodiment of the invention has been disclosed. Sheet material 10^a is shown upon which there is printed or inscribed congruent front and back parts 11^a and 12^a, respectively, contacting at an angle 13^a which will permit the front and back parts to be superimposed when the parts are cut out and bent on said contacting area. The contacting area is so arranged that the parts are printed at an angle to each other. As shown on the drawings the parts are substantially cut out from the sheet 10^a, except for a small piece of the sheet which still remains, merely for illustrative purposes. The front and back parts have integral bases 14 and flanges 16 separated from the bases by score lines 15. The back side of the sheet 10^a is gummed. Removable elements 19 cover a portion of the gummed material immediately behind the flanges 16. These removable elements are in the form of adhesive tape. When removed the gummed portion of the backs of the flanges will be exposed and ready for use. The adhesive tape 19 is shown of a larger size than the flanges, but when the parts are cut out, the tape will simultaneously be cut down to proper size as shown in the cut portion of the figure.

With this form of the invention the gummed material may be moistened for the securing of the front and back parts together without any danger of the gummed material upon the flanges 16 being accidentally moistened. After the front and back parts have been secured together, the adhesive 19 is removed and the gummed material of the flanges may now be moistened to secure the flanges upon a flat base piece, for example, a base piece similar to that indicated by reference numeral 17 in Fig. 3.

It is proposed that the cut-outs be arranged in sets, some of the sets for girls, and others of the sets for boys. Some of the sets will be listed below merely for the purpose of making it clear as to the manner in which the toys may be arranged for sale.

FOR GIRLS

60 DOLL THEATRE

Contents

Eight dolls—Leading lady, leading man, mother, father, vamp, villain, girl friend, boy friend. 65 Proscenium arch.

Two state sets—One interior and the other outdoors, each having a backdrop and four flies, also a floor covering.

Instructions for setting up the theatre can be printed inside the lid of the box or on the leaflet to be enclosed.

All-around-the-world—Sixteen dolls in national costume—Hawaiian, Japanese, Chinese, East Indian, Persian, Moorish, Spanish, Italian, Bulgarian, Swiss, French, Dutch, German, Nor-

wwegian, Irish, and American Betty who goes "all-around-the-world."

Map of the world printed on the inside of box cover with the countries represented connected by a red "travel line".

STORYLAND PEOPLE

Twelve cut-outs: Red Riding Hood, Goldilocks, Cinderella in her gold gown, Sleeping Beauty, Bo-Peep, Boy Blue, Snow White, Hansel and Gretel, Snow Queen, Aladdin and his lamp, Fairy.

10 CUT-OUTS FOR YOUNGER CHILDREN

A FARMYARD IN THE JUNGLE

Twenty cut-outs: Horse, cow, sheep, rooster, hen, three baby chicks, turkey, dog, cat, sparrow, lion, leopard, elephant, bear, thorn fence to surround barnyard, clump of jungle grasses, three jungle trees.

20 WATERFOWLS

Twelve cut-outs: Two white swans, two gray geese, one white duck, and three yellow ducklings, four wild fowls in color. If these are waterproofed with shellac they can be floated.

25 CUT-OUTS FOR BOYS

(Or, they might be ready made)

TRAINS

Locomotives, passenger cars, freight cars, a caboose, etc., which the boy can set up, connect and pull along with a string.

30 YACHTS

Sailing ships and steamers, to be cut-out, pasted and set up, and if waterproofed with shellac they can be floated.

35 NAVY SHIPS

A set of battleships, cruisers, destroyers, subs, tenders, and other types of navy ships, to be cut out and set up, and waterproofed with shellac so that they may be floated. If these ships, yachts, and waterfowls were packed in boxes 45 waterproofed on the inside, the boxes would become ponds in which to float them.

40 ARMY SET

Forts, guns, officers, soldiers, to be cut out, and set up, when they become movable toys which can be played with as those made of metal or wood.

While I have illustrated and described the preferred embodiment of my invention it is to be understood that I do not limit myself to the precise construction herein disclosed and the right is reserved to all changes and modifications coming within the scope of the invention as defined in the appended claims.

Having thus described my invention, what I claim as new and desire to secure by United States Letters Patent is:

1. A blank for cut-out standing toys, comprising a sheet of material printed or inscribed with congruent front and back parts of a figure or object contacting at an area which will permit said front and back parts to be superimposed when the parts are cut out and bent on said contacting area, said parts having integral bases adapted to be bent outwards when the parts are superimposed, the back side of said sheet being provided with material adapted to be moistened to become adhesive, and removable moisture shielding elements covering the adhesive mate- 75

rial and arranged on the back of said bendable integral bases.

2. A blank for cut-out standing toys, comprising a sheet of material printed or inscribed with congruent front and back parts of a figure or object contacting at an area which will permit said front and back parts to be superimposed when the parts are cut out and bent on said contacting area, said parts having integral bases adapted to be bent outwards when the parts are superimposed, the back side of said sheet being provided with material adapted to be moistened to become adhesive, said integral bases having portions divided off by score lines which may be bent outwards to form flanges, and removable elements covering the adhesive material and arranged on the back of said flange portions, said removable elements comprising adhesive tape.

3. A blank for cut-out standing toys, comprising a sheet of material printed or inscribed with congruent front and back parts of a figure or object contacting at an area which will permit said front and back parts to be superimposed when the parts are cut out and bent on said contacting area, said parts having integral bases adapted to be bent outwards when the parts are superimposed, the back side of said sheet being provided with material adapted to be moistened to become adhesive, removable moisture shielding elements covering the adhesive material and arranged on the back of said bendable integral bases, and a flat base piece adapted to be pasted across said bendable bases after said moisture shielding elements have been removed.

ADELE BURNS.
